DESIGN FOR A MULTITUB WASHING MACHINE

Clifford A. M. Weber, Longmeadow, Mass., as-
signor to Westinghouse Electric & Manufactur-
ing Company, a corporation of Pennsylvania

Application February 14, 1934, Serial No. 50,723

Term of patent 7 years

To all whom it may concern:

Be it known that I, CLIFFORD A. M. WEBER, a citizen of the United States, residing at Longmeadow, in the county of Hampden and State of Massachusetts, have invented a new, original, and ornamental Design for a Multi-Tub Washing Machine, of which the following is a specification, reference being had to the accompanying drawing, constituting a part hereof.

Figure 1 is a top plan view of a multi-tub washing machine, showing my new design;

Fig. 2 is a front elevational view; and
Fig. 3 is a side elevation.

I claim:

The ornamental design for a multi-tub washing machine, as shown.

In testimony whereof, I have hereunto subscribed my name this 25th day of January, 1934.

CLIFFORD A. M. WEBER,
